DESIGN FOR A FOOD MIXER

Walter J. Burford, Baltimore, Md.

Application August 31, 1942, Serial No. 108,076

Term of patent 7 years

To all whom it may concern:

Be it known that I, Walter J. Burford, a citizen of the United States of America, residing at Baltimore, State of Maryland, have invented a new, original, and ornamental Design for a Food Mixer, of which the following is a specification, reference being had to the accompanying drawing, forming a part thereof, wherein—

I claim:

The ornamental design for a food mixer, as shown.

WALTER J. BURFORD.
